ATTORNEY

UNITED STATES PATENT OFFICE.

LEVI D. VAN VALKENBURG, OF HOLYOKE, MASSACHUSETTS.

PEN-RETAINER.

1,316,069.

Specification of Letters Patent. Patented Sept. 16, 1919.

Application filed July 30, 1918. Serial No. 247,457.

To all whom it may concern:

Be it known that I, LEVI D. VAN VALKENBURG, a citizen of the United States of America, and resident of Holyoke, in the county 5 of Hampden and State of Massachusetts, have invented certain new and useful Improvements in Pen-Retainers, of which the following is a full, clear, and exact description.

10 This invention relates to improvements in pen retainers or clips, and consists particularly in means for anchoring the pen-retaining device or clip to the pen cap.

One of the objects of the invention is the 15 provision of a pen cap for fountain pens with a retainer secured thereto in such manner that the retainer or clip will not slide or shift in the pen cap, nor be accidentally displaced therefrom, and yet permit of ready 20 detachment from the pen cap when desired.

With the above and other objects in view, the invention consists in certain new and useful combinations, constructions and arrangement of parts clearly described in the 25 following specification and fully illustrated in the accompanying drawings in which:

Figure 1 is a longitudinal sectional view taken through a pen cap showing the construction of the improved retainer.

30 Fig. 2 is a top plan view thereof.

Fig. 3 is a top plan view of the retainer detached from the pen cap.

Fig. 4 is a longitudinal sectional view of a modified form, wherein the retainer or 35 clip is secured directly to a plug threaded to the barrel of the pen cap.

Referring to the accompanying drawings, 5 designates the pen cap which is provided with longitudinal opening 5' extending 40 through the wall thereof, and the upper end of the cap. The cap 5 is also formed with a transverse slot 6 which intersects said opening in the cap 5.

The retaining bar 7 carries on its lower 45 end, a ball point 8, and is provided at its upper end with a lateral ear or anchor flange 9 which is inserted in the transverse slot 6. A pin 10 is disposed in the opening in the wall of the cap 5 and extends across the 50 slot 6 and through an opening 9^a formed in the pen cap retaining bar 7, as shown in Fig. 3. The upper end of the pin 10 is provided with a head 10^a which is counter-sunk in the end wall of the pen cap, so that the 55 pin may be lifted from its socket or open-

ing in said pen cap. The pen cap is also formed with a transverse opening 11 which registers with the opening in which the pin 10 is disposed, so that the pin may be displaced by the insertion of a pointed tool 60 or instrument in the opening 11.

By this means the retaining bar 7 is positively anchored to the pen cap 5 or may be readily detached therefrom by the withdrawal of the pin.

65 In Fig. 4 I show a pen cap 12 in which the screw 13 is threaded. The screw 13 is formed on the end plug 14 which butts against the upper end of the pen cap or barrel tube 12. The plug 14 is formed with a 70 transverse slot in which the flange or anchoring ear 15 of the retaining bar 16 is disposed. The retaining bar 16 is retained in said plug slot by means of the pin 16^a, which is disposed in an opening formed in the plug 14 75 and which extends across the anchoring ear 15, in the manner described with reference to Figs. 1, 2, 3. By this construction the plug 14 forms a carrier for the retaining bar and said retaining bar may be readily 80 detached from the cap by unthreading the plug, or may be removed from the plug by withdrawing the pin 16^a.

85 The plug 14 may be formed with a plain stem which may be fitted in the upper end of the pen cap tube 12, instead of threaded thereto, as shown in Fig. 4.

I claim:

1. A pen retainer consisting of a cap having a transverse slot in one end portion thereof, a retaining bar having a flat terminal portion snugly fitted in said slot, and means extending across said terminal portion and said slot for holding said terminal portion against movement in said slot. 90

95 2. A pen retainer consisting of a cap having a narrow transverse slot therein, a retaining bar having a flat terminal portion disposed in angular relation to the body of said bar and inserted snugly in said slot, 100 said terminal portion having a small hole therein, and a pin disposed longitudinally in said cap and extending through the opening of said terminal portion and across the slot to hold said retaining bar against movement. 105

3. A pen retainer consisting of a pen cap having a plug fitted therein, said plug being provided with a transverse opening, 110 a retaining bar having a lateral portion in-

2
sserted in the opening of the plug, a pin dis-
posed in the plug and extending across the
opening to anchor the retaining bar to the
plug.

5 4. In combination, a pen cap, a plug
fitted therein, said plug having an opening
therein, a retaining bar having a lateral por-

tion inserted in the opening, means for de-
tachably securing the lateral portion in the
opening, said plug forming a carrier for the 10
retaining bar, and removing the retaining
bar from the body of the cap when detached
therefrom.

LEVI D. VAN VALKENBURG.
